(57) **CLAIM**

The ornamental design for a motor mounting bracket, as shown and described.

DESCRIPTION

FIG. 1 is a front elevation view of a motor mounting bracket showing my new design;

FIG. 2 is a top perspective view thereof;

FIG. 3 is a side elevation view thereof; the other side is a mirror image thereto;

FIG. 4 is a top plan view thereof; and,

FIG. 5 is a bottom plan view thereof.

The broken lines in the drawings are included to show unclaimed subject matter only and form no part of the claimed design.
